SLIDE RAIL SUPPORT FOR INDUCTOR
FURNACE WORKPIECES

Harold A. Strickland, Jr., Detroit, Mich., assignor,
by mesne assignments, to The Ohio Crankshaft
Company, Cleveland, Ohio, a corporation of
Ohio

Application April 11, 1946, Serial No. 661,234

6 Claims. (Cl. 219—13)

1

This invention relates to furnace construction, with particular reference to structure for supporting the charge in the furnace chamber.

In induction heating furnaces primarily a tubular heat chamber is provided lined with firebrick or the like in which, as shown in my copending application Serial No. 384,503 for "Electric furnace machine," now Patent No. 2,408,350, a group of axially aligned tubes is embedded in the firebrick but projecting above the inner surface of the firebrick to afford an all-metal grille support for the workpiece. These tubes are laterally displaced along the surface of the firebrick wall. Heretofore the front or inlet extension of these tubes connecting to a source of coolant projected radially from the furnace mouth. These projecting sections afforded no means of support in themselves and hence it became necessary to weld or otherwise secure to the tubing at the inlet end supporting rods which were bolted to the coil supporting structure.

A primary object of this invention is to provide a support tube shape at the mouth end of the furnace which lends itself to easy support of the tubes without requirement for additional fastening means.

Another object of the invention is to provide a support tube structure which will permit easy assembly of the support grille within the furnace coil and into engagement with the external supporting means of the tube.

Still another object is to provide a support tube structure which allows construction of sealing cylinders at the front end of the furnace without important modification of the cylinder.

I attain the above-mentioned objects by the construction hereinafter described and shown in the accompanying figure of the drawing, wherein the vapor-sealing construction is shown in a longitudinal sectional elevation of the furnace unit.

The furnace of the invention as shown is in general similar to that shown in my copending application above referred to. The furnace is in the type of an induction coil unit, generally indicated by the numeral 1. The coil 2 is formed of a number of turns of hollow square conductor appropriately insulated from each other by mica or mica-containing strips and on the inner and outer sides also by mica or mica-containing tubing which is appropriately heat-resistant as well as electrically non-conducting. As shown, there are two layers of tubing interior of the coil, as indicated by the numeral 3. A tube 4 formed of asbestos-containing material, such as Transite, is blocked onto the coil surface to serve as pro-

tection therefor, there being an additional outer tubing of mica insulation intermediate the protective layer and the coil tube. Interior of the inner mica tube insulation is a layer of firebrick in which is embedded axially extending and circumferentially displaced load-bearing rods or rails 5. These rails are hollow for the passage of coolant and bear on their inner surfaces projecting lugs 6 of relatively hard metal which take the friction and wear of the workpiece in its movement in and out of the furnace chamber. These rails also bear butterfly plates 7 which extend over the firebrick edges to retain the same in place. At the rear end of the furnace chamber a push-out rod 8 for forcing out the workpiece after the heating thereof is shown. A holding tube 9 fastened to the casing wall 10 forms a support for the push-out rod.

The furnace coil and associated layers of insulation and firebrick are held in place and supported by end plates 11 and 12 to which the unit is fixed by means of support rods 13. These rods carry end coil springs 14 so that the pressure of the rod acting as a bolt is yieldable between the plates 11 and 12 thus holding the unit yieldably in position. These plates are preferably formed of asbestos-containing material, such as Transite.

Intermediate the rear support plate 11 of the coil unit and the casing 10 is placed a cylindrical drum 15 of insulation material. This drum makes close contact at either end adjacent the adjacent plate and casing surfaces so as to be substantially vapor and gas-proof.

At the front end of the furnace there is positioned a mouthpiece 20 having inwardly and angularly projecting fingers 21, the ends of which being in alignment with the inlet opening of the furnace chamber. This mouthpiece serves as a guide to workpieces being inserted within the furnace. The mouthpiece is supported on the front casing wall 22, as shown. Intermediate the casing 22 and the front Transite plate 12 a second cylindrical insulation drum 23 is provided, similar in placement to the drum 15 at the rear furnace end. This drum 23 also makes close contact with the plate 12 and casing 22 to provide at the front of the furnace a substantially vapor and gas-proof enclosure.

In the disclosure of my copending application hereinabove referred to the projecting ends of the rails at the front end of the furnace are extended outwardly radially to the point of connection with the coolant source or to the flexible couplings employed. This construction requires the

welding of holding rods to the rails at the front end for attachment to the front plate support. In the present arrangement I have found it desirable to reverse the front ends of the rails so that they extend for a short distance parallel to the main rail section in a reverse section 24. This reverse section of each rail is passed through registering openings in the front plate 12, which openings are parallel to the axis of the coil and the main section of the rails. Accordingly, it is apparent that these rails may be slid outwardly for removal or inwardly for assembly as desired and that such rail movement does not disturb the fixed seal of the drum 23. It is noted that this particular hook curvature of the front end of the rails with insertion of the apertures through the plate 12 serves as support means for the front end of the rails making the addition of auxiliary holding means unnecessary. The rear end of the rails is supported by I-bars 25 on the rear support plate 11, as shown.

As exemplifying the electrical conductor system of the furnace there is shown the supply bus bars 26 and 27 spaced by insulation 28 at the base of the furnace. Appropriate taps to the coil are made through bus bars 29 and the end conductors 30 which also supply coolant for the coil. The close placement of the bus bars 26 and 27 is desirable to reduce reactance in the electrical circuit, but such placement brings up the problem of leakage as induced by penetration of oil vapor from the furnace chamber. The arrangement as described hereinabove and illustrated in the drawing effectively obviates leakage and consequently efficiency drop arising from oil vapor penetration.

The showing of the drawing is primarily for illustration of the proper use of the invention. Obviously modifications may be made in the general arrangement and details of the disclosure coming within the scope of the appended claims.

What is claimed is:

1. In furnace construction including a tubular induction heating coil, heat-resistant tubing forming an inner lining for said coil, heat-resistant ceramic tubing within said lining and forming a heat chamber, workpiece-supporting tubes embedded in said ceramic tubing having front ends extending transversely outwardly with reference to the coil axis and terminating in reverse end sections approximately parallel to the main support tube section, and support plates mounted at the coil ends, the plates at the front coil end being apertured to receive the reverse support tube sections.

2. In furnace construction including a tubular induction coil, a lining within and supporting said coil, a grille of axially aligned workpiece-support tubes fixed in said lining, said tubes having front end extensions beyond the coil end, said extensions being reversely turned to form reverse end sections external to the grille, and

end support plates for the coil, the front end plate having direct connection to the reverse end sections of the support tubes.

3. In furnace construction, a tubular refractory lining for the furnace chamber, a plurality of axially aligned and radially displaced support tubes partially embedded in the inner surface of said lining, said tubes having a front furnace end extension having sections outwardly turned relative to the lining tube axis and terminal sections parallel to the lining tube axis, and end supports for said lining and tubes, the terminal front extension of the support tubes being adapted to seat in apertures formed in the front support for holding the tubes and lining in fixed position.

4. In furnace construction having a tubular furnace chamber, a support tube adapted for insertion in said furnace chamber for support of a workpiece to be heated, said tube consisting of an extended section normally positioned within the furnace chamber and a front end section extended outside the chamber, said front end section including a reversely turned terminal parallel to the main straight section of the tube, and a joining connection between the straight section and said terminal.

5. In furnace construction having a tubular furnace chamber, a support tube adapted for insertion in said furnace chamber for support of a workpiece to be heated, said tube consisting of an extended section normally positioned within the furnace chamber and a front end section positioned outside the chamber, said front end section including a reversely turned terminal and a joining section between the extended section and said terminal.

6. In furnace construction, a tubular refractory lining for the furnace chamber, a plurality of axially aligned and radially displaced support tubes secured to the inner surface of said lining, said tubes having a front furnace end extension beyond said lining having sections outwardly turned relative to the lining tube axis and reversely turned terminal sections parallel to the lining tube axis, and end supports for said lining and tubes, the terminal sections of the support tubes being adapted for direct connection to the front support for holding the tubes and lining in fixed position.
